UNITED STATES PATENT OFFICE.

CHARLES J. GRIFFITH, OF ST. LOUIS, MISSOURI.

RAILWAY-CROSSING.

1,049,575.

Specification of Letters Patent.

Patented Jan. 7, 1913.

Application filed March 14, 1912. Serial No. 683,905.

To all whom it may concern:

Be it known that I, CHARLES J. GRIFFITH, a citizen of the United States, residing in St. Louis, Missouri, have invented certain new and useful Improvements in Railway-Crossings, of which the following is a full, clear, and exact description, such as will enable others skilled in the art to which it pertains to make and use the same, reference being had to the accompanying drawings, in which—

Figure 1 is a plan view of a railway crossing of my improved construction. Fig. 2 is a cross-sectional view taken on the line 2—2 of Fig. 1. Fig. 3 is an enlarged cross-sectional view taken on the line 3—3 of Fig. 1. Fig. 4 is a plan view of a modified form of the crossing. Fig. 5 is a cross-sectional view taken on the line 5—5 of Fig. 4.

This invention relates to a railway crossing that is formed in a single piece, preferably by being cast, and the principal objects of my invention are, first, to produce an exceptionally strong rigid cast metal structure that will readily resist wear and vibration to which a railway crossing is ordinarily subjected; second, to produce a railway crossing wherein the crossing rails have hollow triangular body portions surmounted by integral balls and flange guards, and, third, to construct the tops of the intersecting crossing rails in such a manner that the tread surfaces of the car wheels will not bump or pound in passing over the intersecting flange grooves formed in the tops of said rails.

To the above purposes my invention consists in certain features of novelty herein-after more fully described and claimed.

Referring by numerals to the accompanying drawings, 1 designates a base plate and formed integral therewith is a pair of upwardly projecting inclined webs 2, which, together with the base plate 1 form a hollow triangular rail body and the side edges of the base plate project beyond the lower ends of the webs 2 in order to receive the spikes or like fastening devices utilized in anchoring the crossing to the cross ties or foundation. The base plate is perforated at suitable intervals in order to receive the supporting means for the cores that occupy the space within the hollow triangular body when the same is formed. The upper ends of the webs 2 are united and formed integral therewith is a body comprising a ball 3 and an upwardly projecting curved flange guard 4 the upper

end of which guard projects above the plane occupied by the tread surface of the ball. The space between the ball and the flange guard forms the flange groove 5. As shown in Fig. 1, four intersecting crossing rails are formed integral with one another to form my improved crossing, and in casting or forming the same the bottoms of the grooves 5 gradually decline toward the points where said grooves intersect as designated by 5^a, and likewise the top or tread surfaces of the balls 3 gradually decline toward the points of intersection as designated by 5^b. By such construction the flanges of the car wheels engage and ride upon the bottoms of the grooves 5 in passing over the intersecting rails, thereby supporting the wheels and as the tops or tread surfaces of the balls of the rails are depressed or decline toward the points of intersection, the tread surfaces of said wheels are carried across the intersecting grooves without jar or pounding. By forming the intersecting rails integral, I am able to produce a very strong, rigid and substantial structure well able to withstand the jars and vibration to which a crossing is subjected in service, and by the formation of the tops of the crossing rails at the intersecting points I eliminate all jar and pounding and consequent vibration, which ordinarily occurs where the tread surfaces of car wheels drop into intersecting grooves in the tops of crossing rails. By forming the bodies of the rails hollow and making the same triangular in cross-section, I provide a very strong construction which is comparatively light in weight and which can be easily and cheaply formed by casting in a single piece. By inclining the webs 2 all side thrust upon the balls of the rails is taken care of, and by extending the flange guards above the plane occupied by the tops of the balls of the rails the liability of the wheels leaving the crossing rails at the intersecting points is reduced to a minimum.

In the modified construction illustrated in Figs. 4 and 5, the corners of the top surfaces of the balls and flange guards are beveled off or inclined downwardly at the points where the grooves 5 intersect. This construction obviates jar and pounding of the wheels upon the crossing rails even when the bottoms of the flange grooves are worn to a considerable depth.

It will be readily understood that minor changes in the size, form and construction

of the various parts of my improved crossing can be made and substituted for those herein shown and described without departing from the spirit of my invention, the 5 scope of which is set forth in the appended claims.

I claim—

1. The herein described railway crossing comprising intersecting crossing rails 10 formed integral with one another each of which rails comprises a base plate, a pair of inclined webs and a ball and flange guard integral with the upper ends of the inclined webs.
- 15 2. The herein described railway crossing comprising intersecting crossing rails each of which is composed of a hollow triangular body portion and a ball and flange guard surmounting said hollow triangular body 20 portion.
- 25 3. In a railway crossing of the class described, a rail comprising a hollow triangular body portion and a ball and flange guard surmounting said hollow triangular body portion.
- 30 4. In a railway crossing of the class described, a rail comprising a base plate, a pair of inclined webs integral therewith and projecting upwardly therefrom and a ball and flange guard integral with the upper ends of said webs.
- 35 5. In a railway crossing of the class described, a rail comprising a hollow triangular body portion, a ball and flange guard integral with the top of said body portion and there being a flange groove between the ball and flange guard.
- 40 6. In a railway crossing of the class described, intersecting rails each comprising a hollow triangular body portion, a ball and flange guard integral with the top of said body portion, and the tread surfaces of the balls of the rails being gradually inclined downwardly toward the points where the 45 rails intersect.
- 45 7. The herein described railway crossing comprising intersecting crossing rails, each

of which is composed of a hollow triangular body portion, a ball and flange guard surmounting said hollow triangular body portion there being flange grooves between the ball and flange guards and the bottoms of which flange grooves gradually decline toward the points where said grooves intersect. 50

8. In a railway crossing of the class described, a rail comprising a hollow triangular body portion, a ball integral with the top of said hollow body portion, and a flange guard integral with one side of said ball. 55

9. In a railway crossing of the class described, a rail comprising a hollow triangular body portion and a ball integral with the upper end of said hollow triangular body portion. 60

10. The herein described railway crossing comprising intersecting rails each of which is composed of a hollow triangular body portion, a ball and flange guard surmounting said hollow triangular body portion, there being a flange groove between said ball and flange guard, the bottoms of which flange grooves gradually decline toward the points where said grooves intersect and the 70 tread surfaces of which balls gradually incline downwardly toward the points of intersection. 75

11. The herein described railway crossing comprising intersecting rails, each of 80 which is composed of a hollow triangular body portion, a ball integral with the top of said hollow body portion, and the top surfaces of all of the balls of the intersecting rails being beveled off at the corners 85 where said balls intersect.

In testimony whereof I hereunto affix my signature in the presence of two witnesses, this 5th day of March, 1912.

CHARLES J. GRIFFITH.
